UNITED STATES PATENT OFFICE

2,515,655

WALL SUPPORTED JAR CAP WRENCH

Martin S. Kormuth, Charleroi, Pa.

Application April 3, 1947, Serial No. 739,037

2 Claims. (Cl. 81—3.3)

1

The present invention relates to kitchen accessories and appliances, generally speaking, and has more particular reference to a novel and improved gripping and holding device for screw-caps such as are currently used on bottles, jars, and analogous food- and commodity containers.

More specifically, the invention has reference to a wedge-type friction gripping device which is adapted to be attached to a relatively fixed support, such as a wall, window or door frame, cabinet or the like, this in a manner to permit the capped end of the jar to be wedged and held therein in a manner to permit both ends to be applied to the jar for purposes of turning the latter, in relation to the cap and thus removing the cap or simply loosening and starting it in order that it may be wholly unscrewed and removed by hand.

An object of the invention is to provide a simple and practical vise-like gripping and holding device which is suspended on a wall or other stationary surface and which is of simple V-shaped form to aptly and suitably serve the ends wanted.

More specifically, novelty is predicated upon a V-shaped member of resilient stock, the crotch or bight portion thereof being provided with a lateral spacer, the limb portions being jacketed in protector sleeves, and the free end portions of the limbs being so bent and fashioned as to be movably suspended from eye-screws anchored in the wall or in an equivalent support.

Other objects and advantages will become more readily apparent from the following description and the accompanying illustrative drawings.

In the drawings, wherein like numerals are employed to designate like parts throughout the same:

Figure 1 is a perspective view of a cap gripping and holding device constructed in accordance with the invention showing the particular construction thereof and also illustrating the manner in which it is resultfully used;

Figure 2 is a horizontal section taken approximately on the plane of the line 2—2 of Figure 1, looking in the direction of the arrows; and

Figure 3 is a detail section, on an enlarged scale, this on the line 3—3 of Figure 1, also looking in the direction of the arrows.

Referring now to the drawings by distinguishing reference numerals it will be noted that the essential part of the device is of general V-shaped form as denoted at 4, the same being fashioned from a single length of stout wire or a rod of cylindrical cross sectional form. The wire is bent intermediate its ends and the crotch or bight

2

portion 5 is bent laterally to form a combined rest and spacing element. The vertex of the element 5 rests, when in use, against the wall or other supporting surface 6. It thus serves to space the limbs of the V-part, that is the limbs 7 and 8, away from and in substantial parallelism with the support 6. The upper end portions, the free ends, of the limbs are of approximate L-shaped form, the principal lateral bends being denoted by the numeral 9 and the terminal bends by the numerals 10. These terminal bends, which assume horizontal positions, are adapted to be slidably suspended in the eye portions of eye-screws 11 mounted in the wall. The limbs 15 have their intermediate portions encased in jacketing sleeves 12. For reinforcing and stabilizing purposes, I provide an assembling clip or cleat, this being denoted by the numeral 13 and being attached to the converging end portions of the device 4. In other words, where the limbs converge into close proximity, there is a clip 13 and this has hooks 14 which embrace the limbs. The clip serves to limit the degree of spreading of said limbs.

25 The drawings also show an example jar (bottle, tin or other container) which is denoted by the numeral 15 and which has a conventional screw-cap 16.

It is obvious that the limbs are possessed of sufficient inherent resiliency that their normal or natural tendency is to approach one another. The clip 13 with its hooks 14 serves to limit the distance of spreading of convergent ends and the L-shaped styling of the upper free ends of the limbs in conjunction with the eyes serves to limit the outward spreading of the divergent ends. The range of "spread" is such as to accommodate jar caps of different diameters and it is evident that by forcing the cap into place between the spreadable limbs, and by "jamming" same until it is lodged, a friction grip is thus attained and the jar is virtually anchored in a set place. Now, by grasping the jar and turning it in the direction of the arrow A, the cap is held and the jar is partially unscrewed. Once the cap is loosened, the jar and cap are then disengaged from between the limbs and the cap is completely removed by hand.

40 It is to be understood that the tip or vertex portion of the spacer-rest 5 is not fastened permanently to the wall. It simply rests in contact with the wall.

A careful consideration of the foregoing description in conjunction with the invention as illustrated in the drawings will enable the reader to obtain a clear understanding and impression of

the alleged features of merit and novelty sufficient to clarify the construction of the invention as hereinafter claimed.

Minor changes in shape, size, materials and rearrangement of parts may be resorted to in actual practice so long as no departure is made from the invention as claimed.

I claim:

1. A jar cap gripping, holding and loosening device of the type shown and described comprising a substantially V-shaped frame adapted to be suspended for use in a vertical position on a wall or other supporting surface, said frame embodying a pair of resilient limbs converging at corresponding end portions and diverging at their free end portions, the latter end portions of the limbs having substantially rigid L-shaped attaching members, the respective terminals of said members being directed laterally and outwardly and being adapted to be hooked and fastened in screw eyes which are properly attached to the stated supporting surface, the converging end portions of said limbs defining a crotch portion and said crotch portion being bent at right angles to the limbs and parallel to said L-shaped members to provide a spacer, the vertex of which is adapted to rest against said supporting surface.

2. A jar cap gripping, holding and loosening device of the type shown and described comprising a substantially V-shaped frame adapted to be suspended for use in a vertical position on a wall or other supporting surface, said frame

embodying a pair of resilient limbs converging at corresponding end portions and diverging at their free end portions, the latter end portions of the limbs having substantially rigid L-shaped attaching members, the respective terminals of said members being directed laterally and outwardly and being adapted to be hooked and fastened in screw eyes which are properly attached to the stated supporting surface, the converging end portions of said limbs defining a crotch portion and said crotch portion being bent at right angles to the limbs and parallel to said L-shaped members to provide a spacer, the vertex of which is adapted to rest against said supporting surface, and a reinforcing clip having end portions secured around the converging end portions of said limbs adjacent to said spacer.
